UNITED STATES PATENT OFFICE.

JOHN B. DAVIS, OF SPRINGFIELD, MASSACHUSETTS, ASSIGNOR TO GILBERT & BARKER MANUFACTURING COMPANY, A CORPORATION OF MASSACHUSETTS.

DISPENSING PUMP.

Original application filed November 7, 1921, Serial No. 513,369. Divided and this application filed June 2, 1923. Serial No. 643,084.

To all whom it may concern:

Be it known that I, JOHN B. DAVIS, a citizen of the United States, residing at Springfield, in the county of Hampden and 5 State of Massachusetts, have invented new and useful Improvements in Dispensing Pumps, of which the following is a specification.

This invention relates to improvements in 10 dispensing pumps such as are commonly used for dispensing measured quantities of gasoline and the like.

The present application is a division of 15 a copending application for U. S. Letters Patent of John B. Davis, Serial No. 513,369, filed November 7, 1921.

In one aspect, this invention is especially concerned with power-operated dispensing pumps and has for its object to provide 20 means for retarding the speed of such pumps as and when desired.

More particularly, the invention has for 25 an object to provide, in a power-operated pump, a braking device which is manually operable at will to retard or stop the pump.

As to this feature, the invention is an improvement in the mechanism disclosed in 30 U. S. Letters Patent No. 1,456,366, granted May 22, 1923, on an invention of John B.

Davis. Other objects of the invention, together 35 with the features of construction by which they are attained, will be apparent from the following description of the preferred embodiment thereof, illustrated in the accompanying drawings, in which:—

Fig. 1 is a fragmentary sectional elevational view showing the invention as embodied in a power operated dispensing 40 pump;

Fig. 2 is a top plan view of the braking device; and

Fig. 3 is a sectional view taken on the line 3—3 of Fig. 2.

Referring to these drawings: Fig. 1 shows 45 a small portion of a power operated dispensing pump, of the type disclosed in the above named prior patent. The portion of the pump shown is sufficient to illustrate 50 the application of the braking device thereto

and reference to said patent may be had for a more complete disclosure of the pump. In Fig. 1, the pump cylinder is indicated at 5 and its piston rod at 6. The latter carries a cross head 7 to the ends of which 55 are attached depending piston rods 8, disposed one on each side of piston rod 6. These piston rods 8 extend into compressed air cylinders 9, disposed one on each side of cylinder 5. By means disclosed in said patent, compressed air may be admitted to cylinders 9 to simultaneously lift the piston rods 8 and thus the pump piston rod 6. The rods 8 are provided with rack teeth 60 on their back sides with which pinions 10 are meshed, these pinions being fixed to a transversely disposed shaft 11, adapted to be manually turned, as by the crank handle 12, when desired. The pump mechanism described is encased in casing sections 13, 14 65 and 15 and, as shown in the prior patent, convenient access may be had to the section 14 in which the braking device is located.

The braking device is best shown in Figs. 2 and 3 and includes a drum 16 fixedly secured to the shaft 11 of the pump, and a brake shoe 17 cooperating therewith together with means for applying the shoe to the drum. For convenience in assembling the drum upon its shaft the drum is made 70 in two parts divided along an axial plane and clamped together and to the shaft by bolts 18. To provide a maximum area of braking surface, the drum 16 is provided with a deep peripheral groove 19, while the 75 brake shoe is formed with a segmental rib 20 the opposite sides of which are adapted to frictionally engage the side walls of the groove 19. The side walls of the groove 19 are inclined toward the base of the groove 80 and the side walls of the brake shoe rib 20 are similarly inclined to cooperatively engage the walls of the groove. No portions of the brake shoe 17 other than the inclined 85 side walls of the rib 20 are adapted to engage with the brake drum and consequently the corresponding inclined portions of the rib and groove will be brought into cooperative relation by the application of pressure 90 to the outer periphery of the brake shoe. 100

The means for applying pressure to the brake shoe so as to set the brake comprises a lever 21 which is fulcrumed on a stud 22, the latter projecting from a bracket 23 (Fig. 1) which serves to guide one of the operating rods 8 of the pump actuating mechanism. The fulcrumed end of the brake shoe operating lever 21 is forked, as shown, to embrace a pair of lugs 24, which project from the outer periphery of the brake shoe and which in turn embrace the fulcrum stud 22 and serve to position the brake shoe radially with respect to the drum 16 and prevent displacement of the shoe. The forked lower extremities of the lever 21 are provided with cam faces 25 which are adapted to cooperate with flattened faces 26 on the brake shoe to force the latter into engagement with the brake drum. Normally the lever 21 is held in its inoperative position and the brake shoe is maintained disengaged from the brake drum by means of a coil spring 27 which is secured at one end to the brake shoe and at its opposite end to the lever 21.

In operating the described pump by power, through the agency of the compressed air cylinders 9, the pump piston moves substantially uniformly throughout its stroke from the time the power is applied to the cylinders 9 until it is disconnected therefrom, as is usual in all power-operated dispensing pumps so far as the inventor is aware. This arrangement has a disadvantage over hand-operation where the pump piston may be controlled to move as slowly as desired. Thus it frequently happens that the purchaser wishes to fill a tank and yet is doubtful whether the tank will hold the entire quantity dispensed at one stroke of the pump. In such cases the purchaser naturally watches the tank and as it becomes nearly full instructs the operator of the dispensing pump to pump slowly and to be ready to stop at an instant's notice. With the power operated pump as generally provided the above condition cannot be met and there is danger of overflowing the tank.

In accordance with the present invention the braking device provides a means for controlling the speed of the pump piston while the latter is being operated by power so that the speed of the pump may be retarded as and when desired or, if necessary, stopped altogether before it has completed its full stroke. When operating the pump by power, the operating rods 8 and the pump piston will be raised at a substantially uniform speed. At the same time the shaft 11 and the brake drum 16 are set in rotation. In case the operator is instructed to pump slowly he simply depresses the lever 21 until the operating rods 8 and the pump

piston are retarded to the desired degree 65 and if necessary the pump piston may be entirely stopped by the action of the braking device. In any event the braking device permits the operator to control the speed of the pump piston as and when desired, and particularly according to the desire of the purchaser, whereas without such device it is very difficult to obtain the result desired. At best only an approximation of the result can be obtained by a series of stops and starts and the operator does not have complete control of the situation at all times as he does when the braking device above described is employed.

The invention has been disclosed herein, 80 in an embodiment at present preferred, for illustrative purposes, but the scope of the invention is defined by the appended claims rather than by the foregoing description.

Claims:

1. The combination with a brake drum having a peripheral groove therein, of a segmental brake shoe having a part normally loosely received in said groove and held from lateral displacement thereby, an 90 actuating cam for forcing said part against the walls of the groove, a pin on which said cam is pivotally mounted, and a fork like portion on said shoe to straddle said pin.

2. The combination with a brake drum having a peripheral groove therein, of a segmental brake shoe having a part normally loosely received in said groove and held from lateral displacement thereby, an actuating cam for forcing said part against 100 the walls of the groove, a pin on which said cam is pivotally mounted, a fork like portion on said shoe to straddle said pin, and a spring connecting said cam and shoe and tending to hold said part clear of the walls 105 of said groove.

3. The combination with a brake drum, of a segmental brake shoe, a lever having a forked end provided with a cam face, a fixed stud on which said lever is fulcrumed 110 with said cam face in cooperative engagement with the outer face of said shoe and a pair of projections on the outer face of the shoe embracing said stud and embraced by the arms of said forked end to locate 115 said shoe with respect to the lever and drum.

4. The combination with a brake drum, of a segmental brake shoe, a lever having a forked end provided with a cam face, a fixed stud on which said lever is fulcrumed 120 with said cam face in cooperative engagement with the outer face of said shoe, a pair of projections on the outer face of the shoe embracing said stud and embraced by the arms of said forked end to locate said 125 shoe with respect to the lever and drums, and means normally maintaining said lever and shoe in inoperative position.

5. The combination with a brake drum having a peripheral groove therein, of a segmental brake shoe mounted in substantially vertical relation at one side of the drum and having a part normally loosely received in said groove, an operating lever having a fork at one end, a stud on which
- 10 said lever is pivoted adjacent said end, a pair of projections on said shoe intermediate the ends thereof embracing said stud and embraced by the arms of said fork, and a spring connecting said lever to one end of said shoe.

JOHN B. DAVIS.
